CLOTH LAYING-UP MACHINE

Nathan Obedin, Brooklyn, N. Y.

Application February 26, 1945, Serial No. 579,876

5 Claims. (Cl. 270—31)

1

This invention relates to cloth laying-up machines for supporting a bolt of cloth to be placed in superposed layers on a cutting table.

An object of this invention is to provide a laying-up machine mounted for reciprocating movements on a table, the machine having upright end walls and arms pivotally mounted on each of the end walls, and being further provided with bars connecting the arms and with vertically slidable members connecting the arms, whereby when one of the bars is moved to or from the table the other bar is automatically and equally moved in the same direction relative to the table.

Another object of this invention is to mount each vertically slidable connecting member in releasable frictional restraint on an end wall and to mount a compression spring in fixed relation at its upper end on each end wall, the spring being caused to exert pressure on a vertically slidable connecting member at its lower end, whereby upon release of the frictional restraining means, the laying-up bars are automatically raised to an out-of-operative position above the table.

Another object of this invention is to provide means actuated by the movements of the linkage mechanism for automatically indicating by a dial and pointed the number of layers of cloth laid-up on the table.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a side elevation of the cloth laying-up machine embodying the features of this invention.

Figure 2 is a front elevation of the cloth laying-up machine shown in Figure 1.

Figure 3 is a cross-sectional view of mechanism for automatically and equally moving the laying-up or guide rollers to and from the table, the section being taken as on line 3—3 in Figure 2.

Figure 4 is a view of a fragmentary portion of the mechanism shown in Figure 3.

Figure 5 is a view similar to that shown in Figure 3, and showing mechanism for operating a dial.

2

Figure 6 is a view of a fragmentary portion of the dial arrangement.

Figure 7 is a side view of cam mechanism for operating the dial.

In the illustrated embodiment of the invention, the numeral 10 indicates a cloth laying-up machine comprising a carriage or frame 11 and a cutting table 12. The frame 11 has end walls 13, 13'.

The end walls are secured by threaded tubes 14, 14' passing through the walls. Threaded nuts 15 engage the threads on the tubes on opposite sides of the end walls and maintain the end walls in spaced-apart relation.

Grooved wheels 17 are rotatably mounted on studs 18 in legs 19 at the lower portion of the end wall 13 and rest upon a track 20 mounted on one side of the cutting table 12. The end wall 13' is supported by non-grooved or plain rubber wheels 21 rotatably mounted similar to the mounting of the grooved wheels 17 and rest directly on the cutting table 12. The end walls extend upwardly and terminate in bifurcated upper ends 25 adapted to receive a shaft 26 for supporting a roll of cloth indicated by dot-and-dash lines 27. A suitable sheet metal cover 30 is secured to and covers the tubes 14, 14'.

In operation, a roll of cloth 27 which is to be laid-up on the table 12 is supported on the shaft 26. For the purpose of keeping the fabric in an even plane as it is laid-up on the table, the machine comprises guide rollers 30, 31 mounted on two arms 32, 32 which are mounted on pivots 33, 33. The pivots extend respectively from the side walls 13 and 13'.

As shown in Figure 1, the oppositely disposed rollers 30, 31 and the pivots 33, 33 are spaced apart equally from the axis or shaft 26.

For the purpose of automatically and equally moving both arms in the same direction relative to the table as determined by the height of the cloth laid-up, the ends of the arms opposite the rollers have pins 34 fixed therein and extending crosswise from the arms. An elongated horizontally positioned connecting member 35 has elongated slots 36 in which the pins 34 are slidably mounted. A web of the cloth is passed underneath the roller 30 and over the roller 31. The rollers 30, 31 tension the web during the laying-up operation.

The carriage or frame 11 is manually pushed to one end of the table 12 and the web of cloth is weighted down by a metal bar 38. The carriage is then pushed to the opposite end of the table 12 and the web is pulled to that end and another

weighted bar is placed on the web. These movements are repeated until the desired amount of cloth is laid-up on the table.

The connecting member 35 has vertically positioned rectangular guide bars 40 secured thereto in any suitable manner, such as by pins 41. The guide bars 40 are spaced apart and form between them a channel 42.

A vertically elongated rectangular bar 43 is fixed to each end wall by bolts 44. Each bar 43 has an elongated slot 45 centrally thereof. The cross-sectional dimensions of the bar 43 are made to permit the connecting member 35 to be freely slideable in contacting relation therewith.

A hand knob 46, having an integrally threaded bar 47 passing through the slot 45 is in threaded engagement with the connecting member 35. By adjusting the hand knob, the connecting member 35 may be frictionally secured to the rectangular bar 43 in selected vertical positions.

By slightly unscrewing the hand knob, the connecting member 35 is released from excessive frictional restraint. It is thus possible, by moving the laying-up rollers on one side of the carriage 11 from the table 12 to cause both connecting members 35 at opposite end walls 13, 13' to move vertically and to cause the roller on the opposite side of the carriage to move equally vertically in the same direction from the table.

As shown in Figures 4 and 5, a compression spring 48 is held fixed at its upper end by an angle member 49, which is fixed to the wall 13. The lower end of the spring 48 rests on and exerts pressure on the vertically slideable connecting member 35. It will be noted that upon release of the frictional restraining means caused by slightly unthreading of the hand knob 46, that due to the downward pressure of the spring 48 on the connecting member 35, the laying-up rollers will automatically rise to an out-of operation position above the table 12.

Figures 5 and 7 show a modified form of linkage mechanism similar to that shown in Figures 3 and 4 and wherein a modified elongated member 43' extends further upwardly above the hand knob 46 than shown in Figure 3. The member 43' has a slot 45' considerably more elongated than the slot 45 shown in Figure 3.

As best shown in Figure 5, a shaft 57 passes through the slot 45'. An open-face type disc cam 50 is fixed to the shaft 57 and rests on the connecting member 35. It will be seen that when the connecting member 35 is raised or lowered, that the cam will rotate and follow the movements of the connecting member.

As best shown in Figures 6 and 7, a centrally apertured dial 51 is secured to the wall 13 by screws 52 and provides passage therethrough for the shaft 57. The dial has graduations 53. A pointer 54 is fixed to the shaft 57 and has its free end terminating at the graduations 53. It will be noted that when the rollers 31 are moved to and from table 12, that the resulting movements of the connecting member 35 cause the cam 50 to follow the said movements and this causes the pointer 54 to rotate and indicate on the dial the number of layers of fabric layed-up on the table 12.

In accordance with the patent statutes I have described and illustrated the preferred embodiment of my invention, but it will be understood that various changes and modifications can be made therein without departing from the spirit of the invention as defined by the appended claims.

I claim:

1. In a cloth laying-up and feeding machine, a table, a frame having upright end walls mounted on wheels and a transverse roll supporting shaft, said frame being movably mounted lengthwise of said table, two arms pivotally mounted on each of said walls, said arms being spaced apart equally from said shaft, said end walls having upright guide means, an elongated horizontally positioned connecting member slidably mounted on said guide means, and being vertically adjustable, said connecting member having elongated slots at each end, said arms having projecting pins seated in said elongated slots and connecting said arms to said connecting member for movement in coacting relation, laying-up bars connecting said arms, whereby when the free end of one of said arms is moved to or from said table said connecting member is moved vertically and causes the free end of the other arm to move equally in the same direction relative to said table, said arms and said connecting bars serving to support said cloth in laying position and threaded means for frictionally restraining said connecting members for maintaining said laying-up bars in position.
2. In a cloth laying-up and feeding machine, a table, a frame having upright end walls mounted on wheels and a transverse roll supporting shaft, said frame being movably mounted lengthwise of said table, two arms pivotally mounted on each of said walls, said arms being spaced apart equally from said shaft, said end walls having upright guide means, an elongated horizontally positioned connecting member slidably mounted on said guide means, and being vertically adjustable, said connecting member having elongated slots at each end, said arms having projecting pins seated in said elongated slots and connecting said arms to said connecting member for movement in coacting relation, horizontally positioned bars respectively extending between said walls on opposite sides of said shaft and being connected to the lower end portions of said arms, whereby when the free end of one of said arms is moved to or from said table said connecting member is moved vertically and causes the free end of the other arm to move equally in the same direction relative to said table, said arms and said connecting bars serving to support said cloth in laying position and threaded means for frictionally restraining said connecting members for maintaining said laying-up bars in position.
3. In a cloth laying-up and feeding machine, a table, a frame having upright end walls mounted on wheels and a roll supporting shaft, said frame being movably mounted lengthwise of said table, two arms pivotally mounted on each of said walls, said arms being spaced apart equally from said shaft, said end walls having upright guide means, an elongated horizontally positioned connecting member slidably mounted on said guide means, and being vertically adjustable, said connecting member having elongated slots at each end, said arms having projecting pins seated in said elongated slots and connecting said arms to said connecting member for movement in coacting relation, horizontally positioned bars respectively extending between said walls on opposite sides of said shaft and being connected to the lower end portions of said arms, whereby when the free end of one of said arms is moved to or from said table said connecting member is moved vertically and causes the free end of the other arm to move equally in the same direction relative to said table, said arms and said connecting bars serving to support said cloth in laying position and threaded means for frictionally restraining said connecting members for maintaining said laying-up bars in position.
4. In a cloth laying-up and feeding machine, a table, a frame having upright end walls mounted on wheels and a transverse roll supporting shaft, said frame being movably mounted lengthwise of said table, two arms pivotally mounted on each of said walls, said arms being spaced apart equally from said shaft, said end walls having upright guide means, an elongated horizontally positioned connecting member slidably mounted on said guide means, and being vertically adjustable, said connecting member having elongated slots at each end, said arms having projecting pins seated in said elongated slots and connecting said arms to said connecting member for movement in coacting relation, laying-up bars connecting said arms, whereby when the free end of one of said arms is moved to or from said table said connecting member is moved vertically and causes the free end of the other arm to move equally in the same direction relative to said table, said arms and said connecting bars serving to support said cloth in laying position and threaded means for frictionally restraining said connecting members for maintaining said laying-up bars in position.

serving to support said cloth in laying position on opposite sides of said shaft and in a horizontal plane, and releasable means carried by said connecting member and in engagement with said guide means for frictionally restraining said connecting member for maintaining said laying-up bars in position.

4. In a cloth laying-up and feeding machine, a table, a frame having upright end walls mounted on wheels and a roll supporting shaft, said frame being movably mounted lengthwise of said table, two arms pivotally mounted on each of said walls, said arms being spaced apart equally from said shaft, said end walls having upright guide means, an elongated horizontally positioned connecting member slidably mounted on said guide means, and being vertically adjustable on said guide means, said connecting member having elongated slots at each end, said arms having projecting pins seated in said slots and connecting said arms to said connecting member for movement in coacting relation, horizontally positioned bars respectively extending on opposite sides of said shaft and being connected to the lower end portion of said arms, whereby when the free end of one of said arms is moved to or from said table said connecting member is moved vertically and causes the free end of the other arm to move equally in the same direction relative to said table, each of said walls having a compression spring fixed at its upper end and exerting pressure on a connecting member at its lower end, said arms and said connecting bars serving to support said cloth in laying-up position on opposite sides of said shaft and in a horizontal plane, and releasable means carried by said connecting member and in engagement with said guide means for frictionally restraining said connecting member for maintaining said laying-up bars in position.

5. In a cloth laying-up machine, a table, a frame having upright end walls mounted on wheels and a roll supporting shaft, said frame being movably mounted lengthwise of said table, two arms pivotally mounted on each of said walls,

said arms being spaced apart equally from said shaft, said end walls having upright guide means, an elongated horizontally positioned connecting member slidably mounted and vertically adjustable on said guide means, said connecting member having elongated slots at each end, said arms having projecting pins seated in said slots and connecting said arms to said connecting member for movement in coacting relation, horizontally positioned rollers respectively extending on opposite sides of said shaft and being connected to the outer end portion of said arms, whereby when the free end of one of said arms is moved to or from said table said connecting member is moved vertically and causes the free end of the other arm to move equally in the same direction relative to said table, each of said walls having a compression spring exerting pressure on a connecting member, said arms and said connecting rollers serving to support said cloth in laying-up position on opposite sides of said shaft and in a horizontal plane, and releasable means carried by said connecting member and in engagement with said guide means for frictionally restraining said connecting member for maintaining said laying-up rollers in position, release of said frictional restraining means causing said laying-up rollers to be automatically raised to an out-of-operation position above said table.
